HOWARD M. BARBER, OF PAWCATUCK, CONNECTICUT, ASSIGNOR TO C. B. COTTRELL & SONS COMPANY, OF WESTERLY, RHODE ISLAND, A CORPORATION OF DELAWARE.

SIGNATURE-DELIVERY MECHANISM FOR PRINTING PRESSES.

Application filed May 7, 1927. Serial No. 189,552.

My invention relates to certain improvements in signature delivery mechanism for printing presses and particularly to packer deliveries where signatures of one thickness 5 are delivered during one run of the press and signatures of another thickness are delivered during another run of the press, such signatures being delivered vertically into the packer and moved along the same in their vertical position by an intermittently moving endless carrier.

The object of my invention is to provide novel means including an epicyclic gear train for imparting an intermittent movement to 15 the endless carrier, of a predetermined distance and at the desired speed to prevent the smutting or smearing of the signatures as they are moved along the packer.

A practical embodiment of my invention is 20 represented in the accompanying drawings, in which

Fig. 1 represents a detail side elevation of my improved packer delivery.

Fig. 2 represents a similar view of the continuously driven rotary means for imparting 25 the intermittent movement in one direction to the endless carrier of the packer delivery.

Fig. 3 represents a longitudinal vertical section through the packer delivery.

Fig. 4 represents a detail end view of the 30 same.

Fig. 5 represents a detail vertical central section through the epicyclic gear train.

Fig. 6 represents a transverse section taken 35 in the plane of the line VI—VI of Fig. 5, looking in the direction of the arrows.

Fig. 7 represents a transverse section taken in the plane of the line VII—VII of Fig. 5, looking in the direction of the arrows.

The packer delivery table is denoted by 1 40 on which is slidably mounted the packer block 2, as usual. The reciprocating carriage 3 for the packer fingers 4 is provided with the usual rack 5 and pinion 6 by means of which the packer fingers are reciprocated from the cam 7 on the shaft 8 through the rack and pinion 9 and 10. 11, 11 designate the usual side guides for receiving the signatures vertically.

The intermittently moving endless carrier 50 which acts as a traveling support for the signatures is shown as comprising a plurality of endless chains 12 which extend around the curved guides 13 at the inner end of the table 1, idler pulleys 14 at the outer end of the table and sprocket wheels 15 fast on a cross

shaft 16, mounted in suitable brackets 17 projecting from the packer delivery frame 18. The endless chains 12 are kept taut by the belt 60 tightener pulleys 19 carried by the upper ends of the rock arms 20.

The cross shaft 16 is driven from the endless carrier drive shaft 21 through a chain 22 which passes around a sprocket 23 fast on the cross shaft 16 and a sprocket 24 fast on the drive shaft 21.

The epicyclic gear train which is operated to move the endless carrier chains 12 intermittently in one direction a predetermined distance and at the desired speed, is constructed, arranged and operated as follows. 70

A gear 25 concentric with the axis of the drive shaft 21 is made fast to the delivery frame as, for instance, by the screw bolts 26. A corresponding gear 27 concentric with the gear 25 is made fast to the drive shaft 21 as, for instance, by the key 28. This gear 27 has a different number of teeth than the gear 25. In the present instance it has a lesser number of teeth. A two armed lever has its hub 29 rotatably mounted on the drive 80 shaft 21, the arm 30 of which lever is provided with a stud 31 on which is rotatably mounted a wide faced pinion 32 which meshes with both of the gears 25 and 27. The arm 33 of this lever is provided with a stud 34 85 on which are rotatably mounted the pinions 35 and 36, the pinion 35 meshing with the stationary gear 25 and the pinion 36 meshing with the gear 27 fast on the drive shaft 21.

An intermittent rotary movement in one 90 direction is imparted to the two armed lever for imparting an intermittent rotary movement in the opposite direction to the drive shaft 21, as follows:

A ratchet 37 is secured to the hub 29 of the two armed lever as, for instance, by the screw 95 bolts 38. A bolt 39 is mounted on a rock arm 40 pivoted to swing on the drive shaft 21, which arm 40 is oscillated from the continuously rotating crank shaft 41 through a pitman 42 connected at its lower end to the pawl arm 40 and adjustably connected at its upper end at 43 to the crank shaft 41.

By the use of the epicyclic gear train in the mechanism for driving the endless carrier of the packer delivery I am enabled to adjust the movement of the endless carrier to a much more accurate extent to the thickness of the signature being delivered than has heretofore been possible with merely a pawl and 105 110

ratchet connection for this purpose. This minute adjustment is very important in certain classes of products where the thickness of the signatures vary quite materially in one product being delivered during one run of the press over another product being delivered during another run of the press, some of which signatures being so thin that the movement of the carrier could not be adjusted to suit the said signatures.

It is evident that various changes may be resorted to in the construction, form and arrangement of the several parts without departing from the spirit and scope of my invention; hence, I do not wish to be limited to the particular embodiment herein shown and described, but

What I claim is:

1. In a packer delivery for printing presses, an endless carrier acting as a traveling support for signatures of one thickness during one run of the press and for signatures of another thickness during another run of the press, and means including an epicyclic gear train for imparting a predetermined intermittent movement to the carrier corresponding to the thickness of the signatures being delivered to prevent the smutting and smearing of the signatures as they are moved along the packer.
2. In a packer delivery for printing presses, an endless carrier acting as a traveling support for signatures of one thickness during one run of the press and for signatures of another thickness during another run of the press, and means including an epicyclic gear train and a pawl and ratchet drive therefor for imparting a predetermined intermittent movement to the carrier corresponding to the thickness of the signatures being delivered to prevent the smutting and smearing of the signatures as they are moved along the packer.
3. In a packer delivery for printing presses, an endless carrier acting as a traveling support for signatures of one thickness during one run of the press and signatures of another thickness during another run of the press, an endless carrier drive shaft, and means including an epicyclic gear train for imparting a predetermined intermittent movement to the drive shaft and thereby to the carrier corresponding to the thickness of the signatures being delivered to prevent the smutting and smearing of the signatures as they are moved along the packer.

4. In a packer delivery for printing presses, an endless carrier acting as a traveling support for signatures of one thickness during one run of the press and signatures of another thickness during another run of the press, an endless carrier drive shaft, and means including an epicyclic gear train and a pawl and ratchet drive therefor

for imparting a predetermined intermittent movement to the drive shaft and thereby to the carrier corresponding to the thickness of the signatures being delivered to prevent the smutting and smearing of the signatures as they are moved along the packer.

5. In a packer delivery for printing presses, an endless carrier acting as a traveling support for signatures of one thickness during one run of the press and signatures of another thickness during another run of the press, the packer frame, a gear fast thereon, an endless carrier drive shaft, a gear fast thereon concentric with and having a different number of teeth than the frame gear, a two armed lever rotatably mounted on said shaft, a wide faced pinion carried by one arm, meshing with both said gears and two pinions carried by the other arm meshing with their respective gears, and means for imparting a predetermined intermittent movement in one direction to said lever and thereby to the endless carrier corresponding to the thickness of the signatures being delivered to prevent the smutting and smearing of the signatures as they are moved along the packer.

6. In a packer delivery for printing presses, an endless carrier acting as a traveling support for signatures of one thickness during one run of the press and signatures of another thickness during another run of the press, the packer frame, a gear fast thereon, an endless carrier drive shaft, a gear fast thereon concentric with and having a different number of teeth than the frame gear, a two armed lever rotatably mounted on said shaft, a wide faced pinion carried by one arm, meshing with both said gears and two pinions carried by the other arm meshing with their respective gears, a ratchet on said lever, a pawl engaged with said ratchet, and means for oscillating the pawl to impart a predetermined intermittent movement in one direction to the lever and thereby to the endless carrier corresponding to the thickness of the signatures being delivered to prevent the smutting and smearing of the signatures as they are moved along the packer.

7. In a packer delivery for printing presses, an endless carrier acting as a traveling support for signatures of one thickness during one run of the press and signatures of another thickness during another run of the press, the packer frame, a gear fast thereon, an endless carrier drive shaft, a gear fast thereon concentric with and having a different number of teeth than the frame gear, a two armed lever rotatably mounted on said shaft, a wide faced pinion carried by one arm, meshing with both said gears and two pinions carried by the other arm meshing with their respective gears, a ratchet on said lever, a pawl engaged with said ratchet, and a rotary crank shaft connected to said pawl to oscillate it for imparting a predetermined intermittent

movement in one direction to the lever and thereby to the endless carrier corresponding to the thickness of the signatures being delivered to prevent the smutting and smearing 5 of the signatures as they are moved along the packer.

8. In a packer delivery for printing presses, an endless carrier acting as a traveling support for signatures of one thickness during 10 one run of the press and signatures of another thickness during another run of the press, the packer frame, a gear fast thereon, an endless carrier drive shaft gear fast thereon concentric with and having a different number of 15 teeth than the frame gear, a two armed lever having a hub rotatably mounted on said shaft, a wide faced pinion carried by one arm, mesh-

ing with both said gears and two pinions carried by the other arm meshing with their respective gears, a ratchet fast on said lever hub, a pawl engaged with said ratchet, and a rotary crank shaft connected to said pawl to oscillate it for imparting a predetermined movement in one direction to the lever and thereby to the endless carrier corresponding to the thickness of the signatures being delivered to prevent the smutting and smearing of the signatures as they are moved along the packer.

In testimony, that I claim the foregoing 20 as my invention, I have signed my name this 25 fifth day of May, 1927.

HOWARD M. BARBER.
